UNITED STATES PATENT OFFICE.

GEORGE E. FRITTS, OF TAFT, CALIFORNIA, ASSIGNOR, BY MESNE ASSIGNMENTS, TO
F. A. KEEFOVER AND DAISY KEEFOVER.

SUCKER-ROD HANGER.

Application filed May 2, 1923. Serial No. 636,107.

This invention relates to oil well equipment and relates more particularly to a sucker rod hanger by which the sucker rods may be hung when they have been removed 5 from the well.

In the oil well industry, oil is pumped from the wells by means of a pump plunger, which is reciprocated within a pump barrel at the bottom of the well. The plunger is 10 reciprocated by means of mechanism located at the top of the well through a sucker rod string connected therebetween. It is sometimes necessary to remove the string of sucker rod in order to repair or replace parts 15 of the pump plunger or barrel, the sucker rods being uncoupled as they are removed from the well. If these rods are to be stood in the corner of the derrick, they must be uncoupled at each joint because of the flexibility of the rods.

It is an object of the invention to provide a sucker rod hanger which will make it possible for the sucker rods to hang in lengths composed of a number of sucker rods, there- 25 by eliminating the necessity of uncoupling the rods at each joint.

It is a further object of the invention to provide a hanger which will be very easy to manipulate.

30 It is a still further object of the invention to provide a hanger which will engage the upper rod of a stand of sucker rods at a point below the upper end thereof. This feature enables the transfer of the sucker 35 rod stands from the elevator to the hanger and from the hanger to the elevator to be accomplished with increased facility.

The sucker rods are drawn from or lowered into the well by means of an elevator 40 which is placed around the sucker rod just below a shoulder formed at its upper end. By providing a hanger member, which will grip the shank of the rod, a sufficient space at the top end of the sucker rod may be left 45 to allow the removal or engagement of the elevator beneath the head formed at the end of the sucker rod.

The improved hanger member I use consists of a head portion in which a vertical 50 channel is formed. Pivots attached to this head is a lever having an eccentric cam at the end adjacent to the channel in the block or head portion. Attached to the outer end of the lever member is a flexible cable 55 which has its upper end tied to a support-

ing bar mounted in one corner of the derrick. To this supporting bar is attached a multiplicity of similar cables having these clamps at the lower end thereof. When it is desired to hang a length of sucker rods, the 60 clamp is placed on the upper rod just below the elevator so that the rod will extend through the channel in the head, and so that the eccentric cam may grip the rod. When the weight of a length of sucker rods is transferred from the elevator to the cable fixed to the clamp member the eccentric cam will be made to grip the rod because of leverage placed thereon by the lever member. The elevator may then be removed and the 70 rod swung into the corner of the derrick, where it may remain until again placed in the well.

Further objects of the invention and additional advantages will be made evident 75 hereinafter.

Referring to the drawings, which are for illustrative purposes only:

Fig. 1 is a fragmentary perspective of one corner of a derrick showing a form of my 80 invention and illustrating certain features thereof.

Fig. 2 is a plan view of the cable supporting bar, showing how it may be clamped to the corner member of the derrick.

Fig. 3 is a fragmentary elevational view showing how the cable may be conveniently attached to the supporting bar.

Fig. 4 is a plan view of a preferred form of clamp which may be employed in the 90 practice of my invention.

Fig. 5 is an elevation of the clamp shown in Fig. 4.

Fig. 6 is a plan view of an alternative form of clamp which may be used.

Fig. 7 is an elevational view of the clamp shown in Fig. 6.

As shown in Fig. 1, 11 represents a corner of a derrick, of which I show only enough to illustrate the utility of my invention. The derrick is constructed in the usual manner, having corner members 12, girts 14, and diagonals 15. Clamped to the corner member 12 by means of a U bolt 17 and nuts 18, as shown in Fig. 2, is a supporting bar 19. To this bar 19 is attached a number of cables 20, which may be tied to the supporting bar 19 by means of a bowline knot 21 as shown in Fig. 3. Attached to the lower end of each cable is a clamp member 25. It 110

will be understood that any number of cables having clamps fastened thereto may be used, corresponding to the number of sucker rod stands to be held.

- 5 The clamp 25, as shown in Figs. 4 and 5, provides a head portion 26, having a channel 28 formed therein through which the sucker rod 29 extends. Pivotaly mounted on the head 26 by means of a pin 30 is a lever 32. That portion 33 of the member 32 which is adjacent to the channel 28 is of eccentric cam formation as shown, and the opposite end 34 of the member 32 has a cable member 20 tied thereto by means of a bow-line knot 35. When the lever 32 is in the position shown in full lines in Fig. 5, the cam portion 33 is in gripping position relative to the member 29, and when the lever assumes the position indicated by the dotted 10 lines 37 of this figure, the cam portion 33 is disposed away from the rod 28 in a non-gripping position, as shown.

- Again referring to Fig. 1, my invention may be practiced in the following manner: 20 Let it be supposed that the strings of sucker rods 29 supported by the hangers are to be installed in the well. A workman standing on the platform 40 swings one of the stands 29 from its position in the corner of the derrick 25 into a position engaging the slot 41 of the retaining member 42 which is secured to the platform 40. The elevator (not shown) 30 may then be placed just below the shoulder 41 of the rod 29. The weight of the sucker rods 35 may then be changed from the cable 20 to the elevator by raising the elevator. As shown in Fig. 5, the lever 32 may then be swung from its position in full lines to the position indicated by the dotted lines 37 and 40 the clamp easily removed from the sucker rods. After removing the clamp 25 the stand is then screwed to the pump plunger, or to the stand just below, and lowered into the well. The rods may be removed from the 45 well by reversing the operations just described.

- As shown in Figs. 6 and 7, another type of clamp which may be employed with my invention consists of a casting or forging 50, having a head portion 51 from which ex-

tends an arm 52. A cable may be tied to the end 53 of the arm 52 as shown. In the head 51 is a diagonal slot 55, which is enlarged at its inner end as shown, so that the corners 56 and 57 thereof will engage and frictionally grip the rod 58 and thereby retain it in suspension. It will be seen that the leverage ratio between the height of the slot 55 and the length of the arm 52 provides an ample supporting grip upon the shank of the sucker rod to prevent any slippage.

It will readily be perceived that by employing my invention, not only is time and labor saved by avoiding the necessity of uncoupling each sucker rod from the other, but by its use the rods may be gripped below the head in such a manner that the sucker rod elevator may be readily engaged and disengaged.

I claim as my invention:

1. In a sucker rod hanger, the combination of: a cross bar secured to the derrick structure at an elevated point; a plurality of suspension members secured at their upper ends to the cross bar; clamp members secured to the lower ends of said suspension members for gripping stands of sucker rods; a platform situated adjacent to the lower ends of said suspension member; and an inwardly projecting arm having a rest at the inner end thereof for receiving the shank of a sucker rod while the elevator is being adjusted thereupon.

2. In a sucker rod hanger, the combination of: a cross bar secured to the derrick structure at an elevated point; a plurality of freely swingable suspension members secured at their upper ends to the cross bar; clamp members secured to the lower ends of said suspension members for gripping stands of sucker rods; a platform situated adjacent to the lower ends of said suspension members; and an inwardly projecting arm having a rest at the inner end thereof for receiving the shank of a sucker rod while the elevator is being adjusted thereupon.

In testimony whereof, I have hereunto set my hand at Los Angeles, California, this 27th day of April, 1923.

GEORGE E. FRITTS.
